CLAIM

The ornamental design for a vehicle hitch lock, as shown and described.

DESCRIPTION

FIG. 1 is a perspective view of a vehicle hitch lock showing my new design, including a housing, lock pin and padlock, in relation to a trailer hitch shown in phantom lines;

FIG. 2 is a top view thereof;

FIG. 3 is a side view thereof;

FIG. 4 is an opposite side view thereof;

FIG. 5 is a front view thereof; and,

FIG. 6 is a rear view thereof.
